SINGLE ACTION PNEUMATIC RIVETER

Omar E. Clark, Detroit, Mich., assignor to Chicago Pneumatic Tool Company, New York, N. Y., a corporation of New Jersey

Application October 19, 1939, Serial No. 300,185

22 Claims. (Cl. 121—21)

This invention relates generally to fluid pressure operated hammers of the single action type for performing riveting and similar operations and relates more particularly to control means for simplifying and improving the action of such hammers.

Single action or one-shot riveters are used principally in air-craft construction where the majority of the rivets used are small enough to be headed with one or two blows. The usual one-shot tool comprises an elongated cylinder, within which a hammer piston reciprocates, and a handle, connected to the cylinder and containing throttle valve mechanism for controlling the flow of pressure fluid to the ends of the cylinder. The air pressure in back of the hammer piston varies during the impact stroke whereby the force of the blow delivered to the rivet set or working implement is usually less than that theoretically attainable if the air were at the maximum pressure throughout the entire stroke. One of the causes of the pressure variation in tools of ordinary construction is the fact that the hammer piston is permitted to drift forward as soon as the throttle valve starts to open so that by the time that maximum pressure is built up in the rear end of the cylinder the piston has already completed a portion of its stroke. The force of the blow depends largely, therefore, upon the dexterity of the operator in manipulating the throttle lever. The effects of this drifting may be reduced by the provision of yieldable mechanism for retarding initial movement of the piston which, however, does not obviate the necessity for skillful manipulation by the operator or eliminate variations in the force of the blow.

Among the objects of the invention are to increase the power and reduce the air consumption of a one-shot tool of a given size.

Another object is to enable the tool to deliver an impact without the loss of power occasioned by premature initial movement or drifting of the hammer piston.

A feature of the invention is a positive lock preventing the hammer piston from starting on its impact stroke until a predetermined degree of pressure has been established behind the piston.

A further object is to permit the force of blow by the piston to be so delicately adjusted that a substantially perfect rivet head may be driven without leaving the imprint from the rivet set on the soft aluminum sheets being riveted together.

A still further object of the invention is to enable the degree of pressure at which the ham-

mer piston is released to be altered at will in order that the momentum of the piston may be correspondingly altered to suit the requirements of a particular size and kind of rivet.

The present tool is especially suited for use in connection with aluminum alloy rivets. Rivets of such composition have the property of changing their hardness. When first heat treated, the metal is extremely soft but begins to harden almost immediately and will reach maximum hardness in a few hours. As the alloy rivets in a particular lot gradually harden, the operator may make corresponding adjustments from time to time in the force of blow by the piston.

Still another object of the invention is to obviate the necessity for a high degree of skill on the part of the operator. In accordance with this invention, the mechanism which controls the force of blow operates in the same manner irrespective of whether the operator moves the throttle lever quickly or slowly, and is not affected ordinarily by fluctuations in air pressure in the factory main or supply line.

Another feature resides in a calibrated adjusting wrench for the pressure regulating mechanism.

Still another feature resides in a pressure chamber or reservoir forming an energy accumulator and cooperating in the delivery of energy to the hammer piston, at a rate exceeding the rate of supply of potential energy by the air hose, during the power stroke of the piston.

Another object of the invention is to prevent the return of the throttle control mechanism to normal or closed position until the cycle of operation is completed. In carrying out this object there is provided, in the illustrative embodiment of the invention, a yielding means urging the throttle valve to closed position, a latch adapted to retain the throttle valve in position to admit air to the cylinder in a direction to return the hammer piston, and means, operable by the piston at the end of its return stroke, for disabling the latch.

Other objects and features of the invention will be more apparent from the following description when read in conjunction with the accompanying drawings and appended claims.

In the accompanying drawings which illustrate 50 a preferred embodiment of the invention:

Fig. 1 is a view, in longitudinal section, of the tool, showing all parts in normal position;

Fig. 2 is a view similar to Fig. 1, showing the throttle control lever in fully actuated position 55 and the parts in the position they assume dur-

ing the impact stroke after the release of the hammer piston;

Fig. 3 is a view similar to Figs. 1 and 2, showing the parts in the position they assume just prior to the end of the return movement of the hammer piston;

Fig. 4 is a view similar to Figs. 1, 2 and 3, showing all parts in the position they assume at the end of the return movement of the hammer piston just prior to the rebound of the hammer piston from overthrow position to normal position;

Fig. 5 is an enlarged sectional view corresponding to Fig. 3, showing the pressure fluid conducting passageways diagrammatically;

Fig. 6 is a longitudinal section, showing principally the hammer piston latching means, and is taken substantially along the broken line 6—6 of Fig. 2, looking downward;

Fig. 7 is a cross-sectional view, looking forward, of the supporting element for the hammer piston latch;

Fig. 8 is a longitudinal section of the supporting element and is taken along the line 8—8 of Fig. 7;

Fig. 9 is a view, in elevation, of the wrench used to adjust a control device of the tool in order that the force of the blow delivered may be regulated;

Fig. 10 is an end view of the wrench shown in Fig. 9; and

Fig. 11 is a fragmentary view, in section, of the adjusting wrench, and is taken substantially along the line 11—11 of Fig. 9.

The present invention is disclosed as embodied in a small riveting hammer of the one-shot type. As shown in Fig. 1 the hammer comprises generally an elongated cylinder 15 formed with a longitudinal opening or chamber 16 within which a hammer piston 17 reciprocates. Supported at the front end of the cylinder 15 and in axial alignment therewith is a rivet set 18 one end of which extends into the piston chamber 16 in position to be struck by the piston 17. The rivet set 18 is movable within a bushing 19, positioned in the front end of the cylinder 15, and is formed with a collar 21 which engages the outer end of the bushing to limit rearward movement of the rivet set. Forward movement of the rivet set is limited by engagement of the collar 21 with the outer coil of the usual retainer 22 which encircles the front end of the cylinder 15. The rear end of the cylinder 15 extends into a counterbore 23 formed in the front end of a handle 24. The handle 24 and the cylinder 15 are secured together by means of a sleeve 25 which encloses the adjacent ends of the two elements. The sleeve 25 is threaded on to the handle 24 and limits relative movement of the cylinder 15 through a retaining ring 26 which engages complementary recesses in the sleeve and cylinder.

The handle 24 is of generally right angle construction, having a downwardly extending grip portion, containing pressure fluid conducting passages, the throttle control mechanism and other control elements later to be described. A main bore in the handle 24 above the grip portion thereof, forms a pressure chamber 27 which opens directly into the piston chamber 16, within cylinder 15. To effect reciprocation of the hammer piston 17 pressure fluid, preferably compressed air, is directed through the grip portion of the handle and is admitted alternately to the pressure chamber 27 and to the forward end of the piston chamber 16 at a point in front of the

hammer piston 17. The pressure fluid is introduced into the tool through a flexible hose H connected at one end to a suitable source of compressed air and connected at its other end to a plug 28 screwed into the lower end of a bore 29 formed in the grip portion of the handle. The air flows through a port 30, in the plug 28, into the bore 29 and, under the control of a throttle valve 31, is admitted to one or another of a pair of passages 32 and 33 (see Fig. 5) or is prevented from entering either of these passages. The passages 32 and 33 extend upwardly through the handle 24, the passage 32 opening into the pressure chamber 27 while the passage 33 communicates with a longitudinal passage 34 formed in the wall of the cylinder 15. The forward end of the passage 34 communicates, through a valve assembly 35, with the forward end of the piston chamber 16. By reason of this arrangement of passages air, when directed through the passage 32, acts to drive the hammer piston 17 forward through its impact stroke and, when directed through the passage 33, acts to move the hammer piston rearward through its return stroke.

The throttle valve 31, which controls the flow of air to the passages 32 and 33 is of the piston type and is movable vertically within a bushing 36 positioned in the bore 29. Extending throughout the length of the valve 31 is a longitudinal opening 37 the lower end of which is closed by a plug 38. Communication between the longitudinal opening 37 and the bore 29 is established through a set of ports 39 formed in the valve 31 near its lower end. A collar 41 is formed on the lower end of the valve 31, below the ports 39, and is adapted to engage the lower end of the bushing 36 to limit upward movement of the valve and to prevent the flow of air through the ports 39. A compression spring 42 interposed between the lower end of the valve 31 and an inner shoulder of the plug 38 urges the valve upward to the normal position of Fig. 1, in which position communication between the bore 29 and valve opening 37 is cut off by reason of the engagement of collar 41 with the lower end of bushing 36. Also formed in the valve 31 are two more sets of ports 43 and 44 which, in cooperation with associated bushing grooves, establish communication between the valve opening 37 and the respective passages 32 and 33. Referring particularly to Fig. 5, it will be seen that the lower ends of the passages 32 and 33 open into respective grooves 45 and 46 formed in the inner surface of the bore 29. In alignment with the grooves 45 and 46 are respective sets of ports 47 and 48, in the bushing 36, which through associated grooves formed in the inner surface of the bushing communicate with the interior of the bushing. By movement of the valve 31 within the bushing 36 one or another of the sets of ports 43 and 44 may be brought into alignment with its respective set of bushing ports to direct air to one or another of the passages 32 and 33. The ports are so arranged that the setting of the valve 31 in position to admit air to one passage serves also to prevent the flow of air to the other passage. The valve 31 is formed, in addition to the ports 39, 43, and 44, with a groove 49 cut in the outer surface of the valve at a point between the ports 39 and 43. This groove communicates, through a set of bushing ports 51 and groove 52, with a passage 53 leading to exhaust. As shown in Fig. 1, in the upper or normal position of the valve 31 the groove 49 uncovers both sets of bushing ports 47 and 51 and so connects the passage

32, and thereby the pressure chamber 27, to exhaust.

The valve 31 is operated by a manually operable control lever, or trigger, 54 located in a slotted portion 55 of the grip portion of the handle 24. The trigger 54 is movable about a pivot 56 and is formed with a rearwardly extending finger 57 which overlies the upper end of the valve 31 and the upper reduced portion of a plunger 58 which closes the upper end of the valve opening 37 (Fig. 5). A spring 59 positioned within the opening 37 between the plug 38 and the lower end of the plunger 58 urges the plunger toward the finger 57. An abutment collar 61 supported at the upper end of the valve 31 limits its upward movement of the plunger 58.

Due to the pressure of the springs 42 and 59 the several elements comprising the throttle control mechanism normally stand in the position shown in Fig. 1. To initiate a cycle of operation the trigger 54 is depressed from the Fig. 1 to the Fig. 2 position. In moving to the fully actuated position of Fig. 2 the finger 57 of the trigger first moves the plunger 58 downward through the opening 37 and then acts upon the upper surface of the abutment collar 61 to depress the assembly comprising valve 31 and plunger 58, as a unit. The initial relative movement of the plunger 58 serves to close the ports 44 while the subsequent movement of the valve 31 serves to bring the ports 43 opposite the bushing ports 47, and to place the ports 39 below the bushing 36 to admit air to the valve opening 37. The air flows from the opening 37, out the ports 43 to the passage 32 and is thereby directed to the pressure chamber 27 where it is stored momentarily and from whence it later expands to drive the hammer piston 17 through its impact stroke. After the impact has been delivered the trigger 54 is released by the operator and the valve assembly is free to rise under the action of the springs 42 and 59. As shown in Fig. 3, the plunger 58 rises to its normal position relative to the valve immediately upon the release of the trigger whereas the valve 31 is automatically held in a partly actuated position in order that air may be directed through the passage 33 to effect the return of the hammer piston.

The means for holding the valve 31 in partly actuated position includes a latch 62 pivoted, on a pin 63, to swing in a plane parallel to a side wall of the slotted portion 55. The latch 62 is urged in a counter-clockwise direction by a spring 64 and is formed with a shoulder 65 adapted to engage the upper end of the valve 31. As shown in Fig. 1, the shoulder 65 of the latch 62 normally abuts against the side of the valve 31, near its upper end, and is held out of locking position. Upon depression of the valve, however, the latch is permitted to rock in a counter-clockwise direction to the position shown in Figs. 2 and 3 where the shoulder 65 overlies the upper end of the valve. When the trigger 54 is released, the valve 31 moves toward normal position but is prevented from completing its return movement by the latch 62 which holds the valve in the position shown in Fig. 3. In this position of the valve, the ports 43 are out of alignment with their associated bushing ports 47, and so closed, while the ports 44 have been brought opposite the bushing ports 48. Also, the ports 39 still extend slightly below the lower end of the bushing 36 and air continues to flow into the opening 37. Since the ports 43 are now closed and the plunger 58 no longer covers the ports 44, the air from the opening 37

flows through the ports 46 to the passage 33, through the passage 34 and past the valve assembly 35 to the forward end of the piston chamber 16 where it acts to return the hammer piston 17. It will be noted that with the valve 31 in the position shown in Fig. 3 the pressure chamber 27 is connected to exhaust through the groove 49 which uncovers both sets of ports 47 and 51 at this time.

The air will continue to flow in a direction to return the hammer piston as long as the valve 31 is held by the latch 62. Disabling of the latch 62 is brought about automatically by the hammer piston as it reaches the end of its return stroke. The rear end of the hammer piston is formed with a head 66 adapted to extend into the pressure chamber 27 and engage the upper front end of a lever 67 pivotally mounted between a pair of arms 68 of a supporting bracket 69 (see Figs. 6, 7 and 8). The lever 67 extends rearwardly beyond its pivot point and overlies the upper end of a spring pressed plunger 71 which passes downwardly through a bushing 72 and in turn overlies a forwardly extending arm of the latch 62. As the hammer piston reaches the very end of its return stroke (shown in Fig. 4) the head 66 thereof strikes the lever 67 and rocks it in a counter-clockwise direction to depress the plunger 71 and thereby disable the latch 62. Upon disabling of the latch, the valve 31 immediately rises to the normal position of Fig. 1, thereby cutting off the supply of air to the opening 37 and holding the latch 62 in disabled position.

The valve assembly 35 which controls the flow of air to and from the forward end of the piston chamber 16 is similar in construction and operation to that disclosed in the patent to E. W. Stevens No. 2,101,159, issued December 7, 1937, and therefore will be described only briefly herein. The cylinder 15 is formed, near its front end, with a boss 73 containing a recess 74 which opens, through a port 75, into the forward end of the piston chamber 16. The outer end of the boss 73 is closed by a cap 76 and the area thus enclosed by the cap communicates with the passage 34 through a passage 77. Mounted within the recess 74 is a hollow valve 78 movable to an open and closed position with respect to the port 75 and an exhaust port 79. When air is directed through the passages 33 and 34 to return the hammer piston 17 it flows through the passage 77, around the notched lower edge of valve 78, to the recess 74 and presses the valve upward to closed position, while a portion of the air passes through small metering orifice 81 in the valve into the piston chamber 16 for returning the piston 17. During the impact stroke of the tool the air in front of the advancing piston forces the valve 78 downward to the position shown in Fig. 2, and passes to atmosphere through the port 79, which is unrestricted to prevent any appreciable back pressure.

The latching means for the hammer piston comprises an element 82 positioned in the pressure chamber or reservoir 27 and formed with a forwardly extending hook-like portion 83 adapted to engage the head 66 of the piston 17. The latching element 82 is pivotally mounted between the arms 68 of the supporting bracket 69 directly above the previously mentioned lever 67. Referring also to Figs. 6, 7 and 8, the supporting bracket 69 is formed with a circular flange 84, extending into the counterbore 23 in handle 24, and with a cylindrical portion 85

which extends forwardly of the flange 84 into the rear end of the cylinder 15, and provides an opening 88 placing the pressure chamber 27 and the piston chamber 16 in constant communication. The flange 84 lies between the rear end of the cylinder 15 and the inner surface of the counterbore 23, and a locating pin 87 passes through an opening in the flange and engages associated recesses in the cylinder and handle 24 to hold these elements against relative movement. Another opening 88 in the flange 84 connects the air passages 33 and 34.

The rear end of the latching element 82 is bifurcated to form a pair of fingers 89 (Fig. 6) which engage a reduced portion 91 of a plunger 92 extending from the grip portion of the handle 24 upward into the pressure chamber 27. The fingers 89 occupy a position between the full circular head of the plunger 92 and a collar 93 which loosely surrounds the reduced portion 91 of the plunger and is pressed upward by a light compression spring 94. The plunger 92 is movable within a bushing 95 and the lower half of the plunger is hollowed out to receive a compression spring 96, which urges the plunger upwards. The lower end of the spring 96 surrounds a supporting stem 97 which extends below the plunger 92 into a threaded opening 98 cut in the lower end of the handle. The lower end of the stem 97 engages a recessed portion of an adjusting nut 99 movable within the opening 98. It will be evident that upward movement of the nut 99 will serve to increase the pressure with which the spring 96 urges the plunger 92 upwards, whereas downward movement of the adjusting nut serves to lessen or diminish such pressure. Bushing 95 extends for a considerable length in order to minimize leakage of high pressure air from reservoir 27 to opening 98 which is maintained at atmospheric pressure.

As shown in Fig. 1, the plunger 92 is normally positioned with its upper convex and engaging the inside surface of the upper wall of the pressure chamber 27 while the latch 82 is maintained in engaging position by the spring pressed collar 93. The hammer piston is, at this time, at the rear of the piston chamber and is held against forward movement by the engagement of the hook-like portion 88 of element 82, with the head 86 of the piston. Upon operation of the trigger 54 compressed air is admitted to the reservoir 27. Since the air has no means of escape from the pressure chamber 27 at this time the pressure in the chamber increases rapidly and, when high enough to overcome the spring 96, acts on the upper end of the plunger 92 to force it downward to the position shown in Fig. 2. In moving downward the plunger 92 rocks the latching element 82 in a counterclockwise direction to disabled position. The hammer piston is thus released and is immediately driven forward with the full force of the air trapped in the pressure chamber 27. The trapped air acts simultaneously over the entire diameter of hammer piston 17 due to the loose fit of the piston within cylindrical projection 85 on bracket 69. As the air in reservoir 27 expands to drive the piston it is reinforced by live air.

After the impact has been delivered and the trigger 54 released, the pressure chamber 27 is connected to exhaust and the plunger 92 is permitted to rise to normal position. As the hammer piston nears the end of its return stroke the head 86 thereof acts as a cam on the hook-like end of element 82, rocking the element out

of its path, against the tension of spring 94. As soon as the head 86 passes the portion 88, the element 82 snaps back to normal position and the piston is again latched against forward movement. Referring to Fig. 3 it will be seen that at the time the head 86 passes the hook 88, and immediately after that time, the piston is still being driven by return air since the head of the piston has not yet moved to the Fig. 4 position to make contact with the previously mentioned disabling lever 67. Upon operation of the disabling mechanism the valve 81 cuts off the supply of compressed air to the piston chamber 16. The piston 17 rebounds to the Fig. 1 position in which its forward movement is arrested by the hook 88; and the parts remain substantially as shown in Fig. 1 until the operator again depresses the trigger 54 to initiate a new cycle. The use of the latch 82 for holding the hammer piston at the rear end of the piston chamber obviates the necessity, existing in prior structures, for a continuous supply of live air to the front end of the piston chamber during the intervals between operations of the trigger. Accordingly, the present invention results in economy in the matter of air consumption.

It has previously been described how adjustment of the nut 99 serves to vary the force with which the pressure responsive plunger 92 is urged to normal position. By varying the resistance offered by the plunger 92 to pressure within the chamber 27 the peak pressure obtainable in the chamber may be varied and the force of the blow delivered by the hammer piston thereby predetermined in accordance with the size and hardness of the rivet to be headed. In order that full advantage may be taken of this adjustable feature a calibrated wrench is preferably used with the tool. A wrench 100 for this purpose is illustrated in Figs. 9, 10 and 11 and is outlined in broken lines in Fig. 4. It comprises a cylindrical rod 101 insertable in threaded opening 98 in the grip handle 24. The front end of the rod has a hexagonal recess into which is pressed a projection 102 made of hexagonal wrench stock. Projection 102 is adapted to fit in opening 103 in adjusting nut 99. A locating pin 104 is also arranged to project from the front end of the rod 101 and is adapted to fit a recess (not shown) in adjusting nut 99 to insure alignment of the wrench with the nut always at the same angle. The rod is turned by a handle 105 secured to its reduced end. The cylindrical part of the rod has indicia 106 visible at the lower end of the grip handle. The indicia show the number of turns of the adjusting nut 99, which determines the peak pressure in reservoir 27 and consequently the speed and momentum of the hammer piston 17. A chart prepared in terms indicative of the calibrations on the wrench and disclosing the proper setting of the nut 99 for each kind of rivet may be used to facilitate the adjustment and obtain a uniform quality of work. The chart (not shown) preferably should classify the rivets according to size, metallic composition, whether hot or cold, and whether the riveting operation is to be completed by one, two or more blows.

Having determined the proper pressure by reference to the chart, the operator inserts the wrench 100 and turns it to the left or to the right until the desired calibration appears. As long as the adjustment is unchanged, the piston will strike each rivet with the same momentum and, if there is no change in the kind of

rivets, with the same results. It is immaterial whether the operator pulls the lever 64 slowly or quickly. Moreover, variations in the pressure of the air in the factory mains will have no substantial effect on the pressure in reservoir 27 or on the accurate performance of the tool for the reason that the latch releasing means has the effect of a pressure limiting valve and will accurately supply the correct pressure in the reservoir as long as the pressure in the hose H does not fall below the maximum required for the selected rivets.

Preferably the reservoir 27 has a considerable volume in order that the tool may deliver a heavy blow, in comparison with its size, owing to the storage of compressed air prior to the release of hammer piston 17 by the latch 82. Upon release, the piston is actuated not only by the live air concurrently delivered through hose H but also by the expansion of stored air in the reservoir. As the air expands, the stored or potential energy is converted into kinetic energy. Since the kinetic energy has only an extremely short time in which to build up, i. e., while the piston is moving forward, it is very advantageous that the piston may absorb potential energy at a rate exceeding the rate of supply of such energy to the tool through the hose H and plug 28.

While the invention has been herein shown and described in what is considered to be a preferred form, it is to be understood that the invention is not limited to the specific details thereof but covers all changes, modifications and adaptations within the scope of the appended claims.

What is claimed is:

1. In a pneumatic tool, the combination of a piston chamber, a piston movable therein, a pressure chamber in communication with said piston chamber, means for introducing pressure fluid into said pressure chamber to drive said piston, means for positively locking said piston against movement, and pressure responsive means within said pressure chamber for disabling said locking means.

2. In a device of the class described, the combination of a piston chamber, a piston movable therein, a pressure chamber in communication with said piston chamber, means for introducing pressure fluid into said pressure chamber to drive said piston, means for latching said piston against movement, pressure responsive means within said pressure chamber for disabling said latching means, a yielding means opposing movement of said pressure responsive means, and means for adjusting said yielding means to vary the force with which movement of said pressure responsive means is opposed.

3. In a pneumatic hammer, the combination of a piston chamber, a hammer piston movable therein, a pressure chamber in communication with said piston chamber, means for introducing pressure fluid into said pressure chamber to drive said hammer piston, means for locking said hammer piston against movement, and means comprising a spring pressed plunger extending into said pressure chamber for disabling said locking means when a predetermined degree of pressure is reached in said pressure chamber.

4. In a device of the class described, the combination of a piston chamber, a piston movable therein, a pressure chamber in communication

5 with said piston chamber, means for introducing pressure fluid into said pressure chamber to drive said piston, means movable to effective and ineffective positions for latching said piston against movement, a yielding means urging said latching means to effective position, and pressure responsive means within said pressure chamber for moving said latching means to ineffective position.

10 5. In a device of the class described, the combination of a piston chamber, a piston movable therein, a pressure chamber in communication with said piston chamber, means for introducing pressure fluid into said pressure chamber to drive said piston, means movable to effective and ineffective positions for latching said piston against movement, a yielding means urging said latching means to effective position, pressure responsive means within said pressure chamber for moving said latching means to ineffective position, and a yielding means of variable strength resisting operation of said pressure responsive means.

15 6. In a device of the class described, the combination of a cylinder, a piston chamber within said cylinder, a handle connected to one end of said cylinder, a pressure chamber within said handle and in communication with said piston chamber, a piston movable within said piston chamber and projecting into said pressure chamber when positioned at one end of said piston chamber, means for introducing pressure fluid into said pressure chamber to move said piston from one end to the other of said piston chamber, means for mechanically locking said piston against movement, and pressure responsive means within said pressure chamber for disabling said locking means.

20 7. In a device of the class described, the combination of a cylinder, a piston chamber within said cylinder, a handle connected to one end of said cylinder, a pressure chamber within said handle and in communication with said piston chamber, a piston movable within said piston chamber and projecting into said pressure chamber when positioned at one end of said piston chamber, means for introducing pressure fluid into said pressure chamber to move said piston from one end to the other of said piston chamber, and pressure responsive means within said pressure chamber for preventing movement of said piston until a predetermined degree of pressure is reached in said pressure chamber, said means including a latch adapted to engage said piston and a spring pressed plunger movable under the force of pressure fluid in a direction to disable said latch.

25 8. In a device of the class described, the combination of a piston chamber, a piston movable therein, means for introducing pressure fluid into said piston chamber to effect a reciprocating motion of said piston, means for controlling the flow of pressure fluid to said piston chamber including a throttle valve settable from a normal position to a plurality of operating positions, means for latching said throttle valve in one of its operating positions, and means operable by said piston for disabling said latching means.

30 9. In a device of the class described, the combination of a piston chamber, a piston movable within said chamber, means for introducing pressure fluid into said piston chamber to effect a reciprocating motion of said piston, means for

controlling the flow of pressure fluid to said piston chamber including a throttle valve settable from a normal position to a plurality of actuated positions in one of which actuated positions pressure fluid is admitted to said piston chamber in a direction to move said piston through a driving stroke and in another of which actuated positions pressure fluid is admitted to said piston chamber in a direction to move said piston through a return stroke, means for latching said throttle valve in its said last mentioned position, and means operable by said piston at the end of its return stroke for disabling said latching means.

10. In a throttle mechanism for a pneumatic tool, the combination of a bore, means for conducting pressure fluid to said bore, a valve bushing within said bore, a piston valve movable within said bushing, a valve opening within said piston valve, a port establishing communication between said valve opening and said bore whereby pressure fluid is conducted to said opening, a collar formed on the periphery of said valve below said part and adjacent one end of said valve bushing, a yielding means acting on said valve in a direction to press said collar against the end of said bushing to prevent normally the flow of air into said valve opening, a second port in said valve establishing communication between said valve opening and the exterior of the valve, a plunger extending into said valve opening and movable relatively to said valve from an ineffective to an effective position to close said second port, a yielding means urging said plunger to ineffective position, a manually operable lever adapted during a part of its stroke to depress said plunger to effective position and during another part of its stroke to depress said valve and said plunger as a unit to admit air to said valve opening, and means independent of said manually operable lever for latching said valve in depressed position.

11. A pneumatic percussive tool comprising a cylinder providing a piston chamber, a hammer piston reciprocable therein, an inlet for live air, a manually operated throttle valve arranged upon operation thereof to distribute live air from said inlet to the rear part of the piston chamber to drive the piston forward, automatic means responsive to the release of the throttle valve for delivering live air to the front part of the piston chamber to return the piston, and means automatically discontinuing such delivery of air to the front part of the piston chamber upon completion of the return stroke of the piston.

12. A pneumatic percussive tool comprising a cylinder providing a piston chamber, a hammer piston reciprocable therein, an inlet for live air, a manually operated throttle valve arranged upon operation thereof to distribute live air from said inlet to the rear part of the piston chamber to drive the piston forward, automatic means responsive to the release of the throttle valve for delivering live air to the front part of the piston chamber to return the piston, means automatically discontinuing such delivery of air to the front part of the piston chamber upon completion of the return stroke of the piston, and means for positively locking the piston near the rear end of the piston chamber just prior to the completion of the return stroke.

13. A fluid pressure percussive tool of the single impact type comprising a piston chamber

having a reciprocable piston therein, a manually operated throttle valve adapted when in operated position to deliver live pressure fluid to the rear end of the piston to tend to drive it forwardly, means restraining the piston against forward movement while the throttle valve is being operated and while the resultant of fluid pressures in all directions on the piston is in a forward direction and of substantial magnitude, and fluid pressure responsive means for disabling said restraining means.

14. A fluid pressure percussive tool according to claim 13 in which the restraining means comprises a mechanical latch and in which said disabling means operates when the pressure on the rear end of the piston attains a predetermined value.

15. A percussive air operated riveting tool of the one-shot or single impact type comprising a cylinder having a hammer piston reciprocable therein, an energy accumulator associated with said cylinder, means for positively holding said hammer piston against movement while energy is supplied to said accumulator prior to the start of the impact stroke of the piston, and means for delivering such accumulated energy to the piston and simultaneously supplying live air to the rear of the piston during the impact stroke thereof.

16. A percussive air operated riveting tool of the one-shot or single impact type comprising a cylinder having a hammer piston reciprocable therein, an air reservoir having a volume exceeding that of the piston and communicating with the rear end of the cylinder, means for simultaneously holding the piston at the rear end of the cylinder and delivering live air to the reservoir, means for releasing the piston after pressure has been built up in the reservoir, and means for driving the piston forward, subsequent to such release, by the concurrent action of live air and stored air from the reservoir.

17. A percussive air operated tool of the single action type comprising a cylinder, a hammer piston reciprocable therein, an air reservoir having a volume considerably in excess of the volume of the piston and communicating with said cylinder, means for delivering live air to the reservoir, means for restraining said piston against movement while air is stored in said reservoir, and control means for disabling said restraining means to cause said piston to be driven by stored air expanding from the reservoir into the cylinder.

18. A percussive air operated tool of the single action type comprising a cylinder, a piston reciprocable therein through a power stroke and a return stroke, means for directing compressed air to the rear face of the piston to drive said piston on its power stroke, means for restraining said piston against movement on its power stroke, and pressure responsive means for disabling said restraining means when the pressure acting on said piston rises to a predetermined height.

19. A percussive air operated tool according to claim 18, including adjusting mechanism for increasing and reducing the resistance of said pressure responsive means to actuation.

20. In a pneumatic tool, the combination of a piston chamber, a piston reciprocable within said piston chamber through a power stroke and a return stroke, a pressure chamber in communication with said piston chamber, means for introducing pressure fluid into said pressure

chamber to drive said piston on its power stroke, means for restraining said piston against movement on its power stroke, and means operable upon attainment of a predetermined pressure in said pressure chamber for disabling said restraining means.

21. A percussive tool of the single action type, comprising a cylinder, a hammer piston reciprocable within said cylinder and normally held at one end thereof, an energy accumulator acting to deliver energy to said piston, means for supplying energy to said accumulator while said

piston is held against movement, and means operable by said energy accumulator for releasing said piston when the potential energy in said accumulator rises to a predetermined height.

5 22. A percussive tool of the single action type according to claim 21, including means for controlling operation of said releasing means to vary at will the amount of energy which may be stored in said accumulator prior to the release 10 of said piston.

OMAR E. CLARK.

CERTIFICATE OF CORRECTION.

Patent No. 2,241,184.

May 6, 1941.

OMAR E. CLARK.

It is hereby certified that error appears in the printed specification of the above numbered patent requiring correction as follows: Page 4, first column, line 42, for "and" read --end--; page 6, first column, line 24, claim 10, for the word "part" read --port--; line 52, claim 11, after "piston" second occurrence, strike out the period and insert instead a comma; and that the said Letters Patent should be read with this correction therein that the same may conform to the record of the case in the Patent Office.

Signed and sealed this 3rd day of June, A. D. 1941.
